Patented Jan. 29, 1918.

INVENTOR

ROSE S. CARLING

Hazard & Miller

UNITED STATES PATENT OFFICE.

ROSE S. CARLING, OF LOS ANGELES, CALIFORNIA, ASSIGNOR TO PNEUMATIC SURGICAL APPLIANCE COMPANY, OF LOS ANGELES, CALIFORNIA, A CORPORATION OF CALIFORNIA.

ARCH-SUPPORT.

1,254,654.

Specification of Letters Patent. Patented Jan. 29, 1918.

Application filed March 28, 1917. Serial No. 158,048.

To all whom it may concern:

Be it known that I, ROSE S. CARLING, a citizen of the United States, residing at Los Angeles, in the county of Los Angeles and State of California, have invented new and useful Improvements in Arch-Supports, of which the following is a specification.

This invention relates to an arch support and particularly pertains to a pneumatic arch support and a case within which it is removably disposed.

It is an object of this invention to provide an arch support which includes a pliable insole member provided with a simple pocket within which a pneumatic pad may be positioned.

Another object of this invention is to provide a pad which may be inflated to a desired pressure and so constructed as to form a pad of permanent shape and of a configuration which will permit it to properly conform to the instep of the foot.

Another object of this invention is to provide a pad formed with a firm rib which extends along the inner edge of the foot instep and acts to cause the weight of the foot to be thrown upon the outer portion of the instep in a manner to automatically rebuild the broken down arch and exercise the weakened muscles so that the correction will be permanent.

It is a further object of this invention to provide a pneumatic pad, simple in construction and positioned within a combined pocket and insole of simple design and which is not liable to become readily worn or for other reasons discarded.

Other objects will appear hereinafter.

The invention is illustrated, by way of example, in the accompanying drawings in which:

Figure 1 is a view in perspective illustrating the insole and particularly disclosing the pocket construction upon the under side of said sole.

Fig. 2 is a view in transverse section as seen on the line 2—2 of Fig. 1 disclosing the pocket formation and the pneumatic pad positioned therein.

Fig. 3 is an enlarged view in perspective illustrating the pad and its peculiar configuration.

Fig. 4 is a view in transverse section as seen through the pad shown in Fig. 3, particularly disclosing the sectional formation

of the pad and the semi-rigid side wall, as well as the detailed construction thereof.

Referring more particularly to the drawings, 10 indicates a flexible insole preferably formed of a leather sheet strip 11, the under side of which is faced with a piece of felt 12. This insole is substantially the shape of the shoe within which the appliance is placed. One end of the insole is positioned beneath the heel of the foot and the forward end of the sole terminates beneath the ball of the foot, thereby holding the sole member in a firm position.

A pocket 14 is stitched along the inner edge of the insole and is adapted to receive a pneumatic pad 15. This pocket is preferably formed of an outer fabric wall which will bear against the insole of the shoe and an inner fabric wall which terminates at a point adjacent the stitching of the outer wall of the insole. Due to this construction, the pocket may be swung outwardly from the insole and the pad readily inserted or removed therefrom. It will thus be seen that when the pocket is in its folded position, the pad will be firmly held beneath the insole and against movement.

Reference being had to Figs. 3 and 4 of the drawings, it will be seen that the pad is of a peculiar configuration. In plan, the pad is substantially semi-circular and is formed with an air-tight top wall 16 and a similar lower wall 17. These walls are suitably and permanently fastened to each other along their contiguous edges which extend around the semi-circular configuration thereof. The opposite edges which are substantially straight are folded over one another and form a reinforced side wall 18 which is firm and produces a sectional formation, as particularly shown in Fig. 4 of the drawings. It will be understood that this formation substantially corresponds to the contour of the foot instep and that the semi-circular formation of the pad conforms to the area of the entire instep cavity and will permit the outer edge of the instep to bear directly upon the insole and support the major portion of the weight of the body.

A small flat air valve 19 is mounted within one wall of the pad and permits optional inflation of the pad, as desired.

In operation, the pad is inflated to a desired pressure and is then placed within the pocket 14, after which the pocket is folded

down against the insole and the entire appliance is positioned within the shoe. When the shoe is placed upon the foot, the pad will normally conform to the instep and, due to the firm wall 18, will support the broken down bones. When pressure is placed upon the insole and its pad, the firm wall will act to maintain the pad in the sectional position shown in Fig. 4 and will thereby throw the weight of the body upon the outer edge of the foot, at the same time causing this weight to inflate the pad toward the firm wall 18. This will act to automatically apply pressure upon the weakened arch structure and will, in time, strengthen and rebuild the weakened parts.

It will thus be seen that the arch support here provided is simple in its construction and will effectively and positively produce a corrective action upon the weakened foot arch.

While I have shown the preferred form of my arch support as now known to me, it is

evident that various changes in the combination, construction and arrangement of parts may be made by those skilled in the art without departing from the spirit of my invention.

I claim:

1. An arch support comprising a flexible insole, a pocket attached along the inner edge of the insole and adapted to swing outwardly for the insertion of a pneumatic pad, and a pneumatic pad in said pocket; so that the pocket containing the pad swings under the insole and produces an arch support, said support being highest at its longitudinal center and inner edge.

2. An arch support comprising a flexible insole, a pocket attached along the inner edge of the insole and adapted to swing outwardly for the insertion of a pad, and a pad removably inserted in said pocket.

In testimony whereof I have signed my name to this specification.

ROSE S. CARLING.
